UNITED STATES PATENT OFFICE.

DAVID L. GARVER, OF HART, MICHIGAN.

PILE-TRUSS.

SPECIFICATION forming part of Letters Patent No. 655,618, dated August 7, 1900.

Application filed May 6, 1899. Serial No. 715,880. (No model.)

To all whom it may concern:

Be it known that I, DAVID L. GARVER, a citizen of the United States, residing at Hart, in the county of Oceana and State of Michigan, ⁵ have invented an improved Pile-Truss, of which the following is a specification.

It is the object of my invention to provide a cheap, light, and easily-adjustable pile-truss which can be worn with great convenience ¹⁰ and is particularly efficient in function.

In the drawings, Figure 1 is a perspective view of my improved truss, the several parts being shown adjusted relative to each other, as when in use. Fig. 2 is a plan view of the ¹⁵ strap to which the anal bulb or cushion is attached. Fig. 3 is a perspective view of the loop for the anal pad. Fig. 4 is a side view of the anal pad or bulb with loop attached.

My invention is embodied in the construction and arrangement of parts hereinafter described and claimed.

The anal bulb or cushion A is attached to the inner side of the strap B, which in use passes between the legs of the wearer and is ²⁵ buttoned at each end to the body-belt C in front and rear. The front end of said strap B is slitted lengthwise, and thus bifurcated, the two branches diverging from each other at a point opposite the perineum of the wearer.

The conical and slightly-oblance bulb or cushion A is formed by pressing a leather disk into the desired shape and stuffing the cavity with some duly soft and elastic material. The bulb A is secured to strap B by sewing through its flared rim or base-flange. ³⁰

A thumb-strap D is attached to the bulb or cushion A, as shown, by sewing through the ends of the former and flange of the latter. The strap D forms a loop, as shown, which is adapted for use in adjusting the bulb to its ⁴⁰ proper place while the truss is attached to the person.

The strap B and belt C are made of elastic material, and thus adapt themselves to the form and movement of the wearer, so that ⁴⁵ the truss is duly supported and may be worn with ease and comfort.

What I claim is—

The improved truss formed of the body-belt C, the bifurcated strap B, the bulb or cushion attached to said strap, and the thumb-strap D, arranged substantially as shown and described. ⁵⁰

DAVID L. GARVER.
